Primary Examiner — Elizabeth A. Albert*(74) Attorney, Agent, or Firm* — Adrian D. Battison; Ade & Company Inc.; Ryan W. Dupuis(57) **CLAIM**

The ornamental design for a blade for a sickle, as shown and described.

DESCRIPTION

FIG. 1 is an isometric view from the top and one side of the blade for a sickle showing the design.

FIG. 2 is a first side elevational view of the blade for a sickle showing the design.

FIG. 3 is a second side elevational view of the blade for a sickle showing the design.

FIG. 4 is a front elevational view of the blade for a sickle showing the design.

FIG. 5 is a rear elevational view of the blade for a sickle showing the design.

FIG. 6 is a top plan view of the blade for a sickle showing the design; and,

FIG. 7 is a bottom plan view of the blade for a sickle showing the design.

1 Claim, 3 Drawing Sheets(56)
